Frederic E. Kip, Montclair, N. J.

Application August 31, 1934, Serial No. 742,344

1 Claim. (Cl. 40—140)

My invention relates to improvements in signs and particularly to illuminated or luminous signs.

The principal general object of the present invention is to provide means for forming letters, numerals or other figures of a plurality of individual parts or sections each provided with light reflecting elements, whereby when the letters or numerals are built up or formed, the same will be visible by day, and when a beam of light is projected on the sign, the reflectors in their alined or assembled relation will be illuminated to exhibit the letters or numerals in the dark.

Another object of the invention is to effect clear formation of the illuminated letters or numerals by so arranging the reflectors on the sections as to provide for alinement of the reflectors along vertical and horizontal or other intersecting lines, when the sections are assembled.

In the accompanying drawing forming a part of this application, I have shown the invention applied to one form of sign of the interchangeable sectional letter type, wherein the sections of which the letters or numbers are formed are provided with means to detachably hold them in place in assembled relation.

In the drawing.

Fig. 1 is a perspective view of a sign of the type above mentioned showing my invention applied thereto;

Fig. 2 is a perspective view of one of the sections of the numerals or letters shown in Fig. 1 showing a modification of my invention;

Figs. 3 and 4 are views similar to Fig. 2 showing further modifications of my invention;

Fig. 5 is an enlarged sectional view taken on the line 5—5 of Fig. 1; and

Fig. 6 is a view similar to Figs. 2, 3 and 4 showing another modification.

In Fig. 1 the numeral 6 designates the sides of the frame, and on which the sign stands. I have shown two similar frames hinged together at their tops in known manner, so that the sign is provided with two opposite faces. This, however, is not essential to the invention. Between the sides 6 are a plurality of transverse equally spaced rods 7 and channel members 8, which latter receive the upper and lower ends of U-shaped plates 9. The rods 7 extend through the sides 6 of the plates 9, and the sides of the plates are slightly spaced to provide slots 10 therebetween. Above and below the channel members 8 and between the sides 6 there may be provided panels 11 to receive advertising indicia or the like.

The letters are formed from a plurality of sec-

tions or elements designated generally by the numeral 12, each being U-shaped and provided at predetermined points on its sides 13 with bayonet slots 14 to engage the rods 7 when the sides 13 are inserted through the slots 10, as shown in Fig. 1. These sections may be of any desired color to contrast with the background, and I have illustrated them as being red by the lining thereon in Fig. 1. In building up the letters or numerals, one starts with the lowermost sections and builds upwardly by inserting the sides 13 through the slots 10 and engaging the bayonet slots 14 with the rods 7.

The above construction of sign is purely illustrative, as I may use any construction of detachable, interchangeable sectional letter signs in practicing my invention.

My invention resides in the provision of reflecting or illuminating elements mounted in the front or face of the elements 12. In Figs. 1 and 5, I have shown a single substantially circular reflector or prism 15 of appreciable size mounted centrally in the front of each of the sections 12 forming the numeral 16. Each reflector may be secured in place by stamping out of the wall prongs or channels 16' to receive the inner ends of the reflectors, and of course if desired, the reflectors may be cemented to the prongs or channels 16'. In the form of the invention shown in Figs. 1 and 5 where a reflector or prism of appreciable size is mounted substantially centrally in each of the sections 12, the reflectors or prisms, when the letters or numerals are formed by assembling the sections 12, are alined horizontally and vertically in the parts of the various letters or numerals. For instance, it will be noticed that the topmost and the three lowermost reflectors in the numeral 1 are in horizontal alinement, while the intermediate reflectors are in vertical alinement with one of the topmost and one of the lowermost reflectors, so that when a beam of light is projected on the reflectors, the numeral 1 will stand out illuminated against the base of the sign. The same is true of the numeral 6 forming part of 16, wherein the reflectors are in both horizontal and vertical alinement. It should be obvious without illustrating the various letters of the alphabet and all of the numerals 1 to 9, that the sections may be so arranged on the sign as to form various combinations of numbers or letters as desired. This is particularly valuable in connection with signs at gasoline filling stations, for instance, where the prices change frequently, and where motorists driving along the road at

night will see the price illuminated before driving into the station.

Also in Fig. 1 I have shown some of the sections 12 provided with smaller reflectors 17 arranged 5 to permit the formation of fractions. These smaller reflectors may be inserted and secured in the face of the sections in the manner shown in Fig. 5 or by any other suitable means.

It is not essential to the practice of the invention to provide reflectors of the exact character 10 and mounted in the exact positions of those shown in Fig. 1, because as shown in Figs. 2, 3, 4 and 6, other arrangements and shapes of reflectors may be made and provided.

15 Referring to Fig. 2, it will be noted that three relatively small reflectors 18 are shown mounted in the front of one of the sections 12 and alined horizontally thereacross. This section of course would be used to form one of the horizontal parts 20 of a letter or numeral, due to the fact that the reflectors are arranged transversely across the section. Obviously on other sections reflectors 18 could be alined in a vertical plane, so as to form a vertical part of a letter or numeral. This feature is illustrated clearly in connection with the modification of Figs. 3 and 4.

25 In Fig. 3 a rectangular relatively long reflector 19 is mounted transversely across the front of one of the sections 12 and may be held in place in the same manner as the reflector of Figs. 1 and 5.

Under the modifications of Figs. 2—3, the numerals or letters would be built up in the same manner explained in connection with the illustration of Fig. 1 selecting those sections which 30 have the reflectors arranged transversely thereacross to form horizontal parts of the numerals or letters and those sections which have the reflectors arranged longitudinally thereof to form vertical parts of the letters.

40 In Fig. 4 the reflector 20 is of the same length as the section 12', extending from top to bottom thereof, and being set in a groove or channel 21 which also extends from top to bottom of the section and being stamped or otherwise formed 45 as a part of the section, when the sections are made of metal.

In Fig. 6, the section 12'' has the entire front 45 depressed with a portion thereof folded down against the side 13 as at 22, forming a recess of the same size as the reflector 23 which covers substantially the entire face of the section. Obviously, a reflector 20 such as that shown in Fig. 4 could be set in the section 12'' to extend substantially all the way thereacross, to form a substantially solid or continuous luminous letter or numeral.

With reflectors arranged as shown and described in connection with Figs. 2—4, it is neces-

sary to select particular sections in building up numerals or letters, whereas under the arrangements of Figs. 1 and 6, all of the reflectors are adapted for use either as parts of the vertical or horizontal portions of numerals or letters; and 5 under the form of the invention shown in Fig. 6 the luminous letter is solid with the unnoticeable exception of the slight spaces formed by the folds 22 between the horizontally arranged sections.

Of course the sections, under the embodiment 10 of the invention shown in Figs. 1—5 will be painted or colored to contrast with the background on which they are mounted, and I prefer to have the reflectors formed of substantially the same color as that of the sections. For instance, as 15 mentioned above, the sections are illustrated as being red; in such case I would prefer to use red reflectors, or if the sections were yellow or orange, for instance, I would use reflectors of a corresponding color so that the appearance of the 20 sign would be substantially uniform in daylight. However, the reflectors need not be glass prisms, so far as the invention is concerned, and need not necessarily match the color of the sections, as I may use metal foil protected by a glass or other 25 transparent covering instead of glass prisms as reflectors. Under the arrangement shown in Fig. 6 the reflector may be of any color, since they form the entire letter visible both in daylight and at night when a beam of light is projected thereon. 30

I also wish it to be understood that it is not material to the invention how the sections or elements forming the letters are attached to the supporting surface or background of the sign, nor of what material they are made, but only that the 35 reflectors be provided in such a manner as to permit formation of various numerals and/or letters and be properly alined both in vertical and horizontal planes to clearly exhibit the letters or numerals both in daylight and by reflection in 40 luminous form at night.

I claim:

A sign comprising a plurality of elements 45 adapted to be assembled to form numerals or letters, a support for said elements presenting a substantially solid background, means to hold said elements in assembled relation on said support and permitting said elements to be interchanged and rearranged to form various numerals or letters, and light reflectors on the fronts of said 50 elements and arranged so as to be alined in horizontal and vertical planes to form and exhibit the particular letters or numerals formed by the elements when a beam of light is projected on the sign, said reflectors on some of the elements being 55 arranged transversely thereof and on other elements being arranged longitudinally thereof.

FREDERIC E. KIP.
